UNITED STATES PATENT OFFICE.

CHARLES W. UNKLE AND THEODORE D. GRILEY, OF BALTIMORE, OHIO.

ART OF SEPARATING PAPER PULP.

Application filed June 3, 1918, Serial No. 237,863. Renewed May 1, 1922. Serial No. 557,779.

To all whom it may concern:

Be it known that we, CHARLES W. UNKLE and THEODORE D. GRILEY, citizens of the United States, residing at Baltimore, in the county of Fairfield and State of Ohio, have invented a certain new and useful Improvement in the Art of Separating Paper Pulp, of which the following is a specification.

10 This invention relates to the art of separating the finished from the unfinished pulp in tub beaters. In carrying out our invention we utilize centrifugal action and can employ the machine shown and described 15 herein.

In said drawing—

Figure 1 is a top plan view with portions in section.

Fig. 2 is a partial section on the line 20 II—II Fig. 1, looking to the left.

In the views 5 designates the elongated tub in which the paper to be pulped with the necessary water or other liquids used in the process are placed. Secured in this 25 tub longitudinally is the usual mid-feather 6 of such length and so placed as to permit a circulation of the material around the tub when it is impelled at one side of the mid-feather.

30 In one of the spaces between the mid-feather and a side of the tub is the usual roll 7 of wood and containing knives or fly-bars cooperating with the usual bed plate (not shown) in the bottom below. The roll is 35 fastened to a shaft 8 provided with a belt pulley as at 9 for driving the roll. The tub also contains the usual back fall at 10.

The roll is inclosed at its upper side in a hood 11 and in a flattened portion at 12 of 40 that side of the hood opposite the back fall we provide a series of perforations 13. Secured on a rod 14 lying on the flat portion 12 is a series of plates 15 having sharp edges so that when the rod is reciprocated the 45 plates cut portions of the paper stock protruding through all the perforations and clear them for the passage of material as hereinafter further explained.

To reciprocate the rod we provide the following means:

That end of the shaft containing the roll is provided with a spur gear 16 to mesh with a spur gear 17 journaled in a suitable bracket 18. The spur gear 17 has connected with it a beveled gear 19 which in turn meshes with a beveled gear 20 on one end of a short shaft 21 journaled in suitable bracket 22 on the side of the tub. The other end of the shaft 21 is provided with a disk 23 having a crank pin 24 that works in a slotted yoke 60 25 secured to the end of the aforesaid rod 14. When the shaft 8 is rotated, therefore, the revolution of the crank pin 24 imparts a rectilinear reciprocating motion to the rod 14.

Located below the perforations 13 is an inclined trough or gutter 26 which is extended to beyond the opposite side of the tub so as to discharge the pulp into a suitable receptacle placed there for the purpose.

The gutter 26 has a lateral discharge 27 into the tub beyond the mid-feather.

28 designates a removable gate fitting in grooves 29 of the lateral discharge 27 so that the contents of the gutter will be directed to the receptacle beyond the tub. When said receptacle is to be removed or changed the gate 28 is placed in the grooves 30 thereby causing the contents of the gutter to discharge into the tub. The flow of the contents of the gutter can thus be changed without stopping the pulping operation.

In practice the roll is turned in the direction of the arrow Fig. 2 and centrifugal action throws the stock against the inner 85 side of the flat portion 12. The perforations permit the sufficiently reduced portions to pass through said perforations and into the gutter. The larger portions clog and protrude through said perforations but are 90 cut off, removed or pushed back into the tub by the reciprocated plates 15.

What we claim is:

1. In the art of pulping paper the process of continuously separating the sufficiently 95 reduced portions of pulp from the insuf-

ficiently reduced portions during the grinding operation consisting in projecting both portions by centrifugal action directly against a screen and at angles thereto, said
5 screen adapted to permit the passage of the sufficiently reduced portions and in the meanwhile clearing the insufficiently reduced portions from said screen.

2. In the art of pulping paper the process
10 of separating the sufficiently reduced por-

tions of the pulp from the insufficiently reduced portions during the grinding operation consisting in projecting both portions by centrifugal action directly against a screen to permit the passage of the sufficiently reduced portions and meanwhile scraping the insufficiently reduced portions from said screen. 15

CHARLES W. UNKLE.
THEODORE D. GRILEY
